(57) **CLAIM**

The ornamental design for a cradle for a mobile communication device, as shown and described.

DESCRIPTION

This application is also related to co-pending U.S. patent application Ser. No. 29/400,484, filed Aug. 29, 2011, and entitled “Cradle for a Mobile Communication Device”, which is incorporated herein by reference in its entirety.

FIG. 1 is a perspective view of a cradle for a mobile communication device showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines indicate portions of the cradle for a mobile communication device that form no part of the claimed design.
